UNITED STATES PATENT OFFICE.

WALTER S. ROCKWELL, OF NEW YORK, N. Y., ASSIGNOR TO W. S. ROCKWELL COMPANY,
OF NEW YORK, N. Y., A CORPORATION OF NEW JERSEY.

HEATING-FURNACE.

1,289,547.

Specification of Letters Patent. Patented Dec. 31, 1918.

Application filed August 20, 1918. Serial No. 250,652.

To all whom it may concern:

Be it known that I, WALTER S. ROCKWELL, a citizen of the United States, residing at 300 West 106 street, New York, county of New York, and State of New York, have invented certain new and useful Improvements in Heating-Furnaces, fully described and represented in the following specification and accompanying drawings, forming a 10 part of the same.

This invention relates to that class of metal heating-furnaces which is especially adapted to the heating of large ingots, forgings, or other objects which should be subjected to heat equally upon all sides, to heat them through uniformly with the least delay.

Such furnaces may be made twenty or sixty feet long and can operate upon ingots, forgings, or other articles of such weight 15 that they require a car for introducing them into the furnace and supporting them while heating.

In such furnaces it is desirable to introduce heat at various parts of the heating-chamber and to circulate the live flaming gases through the bottom of the heating-chamber, and to control the egress of the highly heated spent gases of combustion from different parts of the chamber, so as to 20 exert a greater or less heating effect upon any particular part of the charge.

The present invention furnishes means for introducing the flaming gases from liquid fuel-burners into different parts of the heating-chamber and to control their circulation through the bottom of the heating-chamber; also the egress of the spent gases therefrom at various parts of the chamber, whereby it provides means for 25 equally heating the floor of the chamber and the bottom of the charge without locating a combustion-chamber beneath the floor, which would render the floor unable to support the heavy loads contemplated.

My construction is thus completely adapted to heat the bottom of the charge at the same time and equally with the top, and to subject any particular linear part of the charge to a higher temperature than other parts, and to safely sustain any required load.

The invention will be understood by reference to the annexed drawing, in which

Figure 1 is a horizontal section on line 1—1 in Fig. 3; Fig. 2 is a longitudinal vertical section on line 2—2 in Fig. 1; Fig. 3 is a cross section on line 3—3 in Fig. 1; and Fig. 4 is a cross section on line 4—4 in Fig. 1.

a designates the heating-chamber with doorway *b* and door *b'* at one end, rear wall *c* at the opposite end, and side-walls *d*, *d'* at its opposite sides.

Along the bottoms of the side-walls so-called main ledges *e*, *e'* are extended longitudinally, being projected upwardly from the chamber-floor far enough to admit spent gas outlet-flues *f* in their bodies and to intercept the flaming gases from the burner-openings *g* located in the side-walls a little above the floor-level and provided with fluid fuel-burners *g'*.

The outlet-flues enter the ledges laterally close to the floor of the heating-chamber, and thus draw the escaping gases downward close to the charge upon the floor.

Four of these burners are shown in the drawing, two in each side-wall, each of the said burner-openings being connected by an up-going vertical flame-duct *h* with two horizontal flaming gas-ducts *i* located beneath the floor *j* of the heating-chamber, each duct *i* having a down-going flame-duct *k* at the end opposite to that which connects with the burner-openings. These ducts *k* originate in supplemental ledges or ridges *k'* at the sides of the chamber-floor *j*, such ridges preventing any objects lying upon the floor from covering the said ducts.

The inner face of the main ledge *e* or *e'*, next to each burner-opening, is formed as a recess or pocket *e''* into which the flaming gases are projected; and which permits their expansion laterally while it forces them upwardly, to circulate in the upper part of the chamber, and downwardly beneath the bottom of the chamber.

Arrows *o* show the circulation of the flaming gases through the heating-chamber and ducts *k*, *i*, *h*.

Arrows *o'* show the path of the spent gases through the outlet-flues *f*.

The heating of the floor, which is very desirable to secure a uniform heat in a heavy forging or other charge, is effected by two means, first, by the flame-ducts *k*, *i*, *h*, which 10 extend beneath the floor and receive the

flaming gases; and second, by the discharge of the spent gases through outlet-flues *f*, close to the floor, so that the spent gases are necessarily drawn downward to escape from the chamber.

5 The outlet-flues *f* may be extended to a stack or any other delivery point, and are shown in the drawing extended upwardly into the side-walls of the furnace at the left-hand side of Fig. 3, and the right-hand side of Fig. 4.

10 Dampers *f'* may be applied to the upper ends of these outlet-flues, of which two are provided on each side of the heating-chamber, to limit the escape of the spent gases from any quarter of the chamber at pleasure, and provide for regulating the heat as desired.

15 The flaming gases are drawn into and through the flame-ducts *k*, *i*, *h*, by the ejector effect of the burners in the burner-openings *g*.

20 Two of the flame-ducts under the floor are connected with each of the burners, so as to multiply the heating effect without unduly increasing the number of burners, two ducts being connected at one end to each burner-opening by the up-going duct *h*. The alternate burner-openings *g* are located respectively in the opposite walls of the furnace, as shown in Figs. 3 and 4, so that the heat is more equally distributed, and the flaming gas-ducts *i* for one-half of the burners are disposed between those for the other half.

25 35 The ducts *i* are separated by partitions *l*, except where connected to the burner-openings by the up-going ducts *h*, which partitions form firm supports for the floor, so as to sustain any desired load. The multiplication of the ducts increases the number of partitions, so that an efficient heating of the floor is secured without weakening its supporting power.

40 45 To carry heavy charges into the furnace, a car is generally used. Such a car is indicated by dotted lines *m* in Figs. 2 and 3, sustained by balls *n* fitted to roll upon grooved track-rails *n*, which are necessarily extended outside the furnace-door, as indicated in Figs. 1 and 2, to sustain the car when withdrawn. The car is not shown in full lines, as it would obscure the openings of the outlet-flues *f*; and the ingot *p* which is shown upon the car in Fig. 3 is omitted in Fig. 2, 55 as it would confuse the drawing.

50 55 In the operation of such a car, the balls assume various positions upon the track-rails, and to prevent any of the balls from jamming against the rear wall of the heating-chamber, outlet-passages *g* are formed through the rear walls in line with the track-rails, and the said rails extended thereinto.

60 65 A hinged flap *r* is shown fitted to the outer end of each passage, which permits any balls

that become crowded into the passage to escape by lifting the flap and rolling out upon the floor. After such occasions, the flap closes automatically to prevent the escape of heat from the chamber.

70

In furnaces employing such a car the external floor *s* is commonly at the same level as the bottom of the heating-chamber, so that the car can be readily loaded and unloaded while standing upon the floor outside of the said chamber.

75 The arrows *o'* show the circulation of the gases about the ingot *p*, such circulation through the various flues and flame-ducts cooperating to heat the floor, and bring the circulating gases into contact with all parts of the charge upon the car, which charge would thus be equally heated on all sides.

80 85 My prior Patent, No. 1,193,824, utilizes a single burner and a single gas-duct below its floor; and I do not therefore claim such a construction broadly herein.

Having thus set forth the nature of the invention what is claimed herein is:

90 1. In a metal heating-furnace, the combination, with a heating-chamber having a plurality of burner-openings in each of its opposite side-walls with fluid fuel-burners arranged to introduce flaming gases above the chamber-floor, of a flaming gas-duct below the floor of the heating-chamber for each of the said burners, an up-going flame-duct connecting the said gas-duct at one end to one of the burner-openings, and a down-going flame-duct connecting the opposite end 10 of the gas-duct with the heating-chamber through the floor of the same, an outlet-flue extended into the side-wall adjacent to each of the down-going flame-ducts, the burner-openings and the outlet-flues being arranged alternately in the opposite side walls, whereby the flaming gas-ducts are located beneath the floor for the burners in one side-wall, intermediate to the flaming gas-ducts connected with the burners in the opposite side-wall.

11 2. In a metal heating-furnace, the combination, with a heating-chamber having a burner-opening in the side-wall with a fluid fuel-burner arranged to introduce flaming gases adjacent to the floor, a ledge upon the floor of the heating-chamber before the burner-opening to deflect the flaming gases therefrom, a flaming gas-duct below the floor connected at one end with the burner-opening, a down-going flame-duct extended through the chamber-floor to the other end of the flaming gas-duct to introduce the flaming gas thereto, and an outlet-flue extended into the ledge near such down-going duct.

3. In a metal heating-furnace, the combination, with a furnace-chamber having a plurality of burner-openings in each of its opposite sides, of main ledges extended

- along the side-walls, and supplemental smaller ledges along the sides of the working-floor, the main ledges operating upon one side of the chamber to deflect the gases 5 from the burners, and the main ledge upon the opposite side of the chamber having outlet-flues extended laterally in the ledge, at least one flaming gas-duct located below the floor and connected at one end to the burner- 10 opening, and having at its opposite end a down-going duct extended through the supplemental ledge to introduce the flaming gases into the flaming gas-duct.
4. In a metal heating-furnace, the combination, with a heating-chamber having a 15 ledge extended along the edge of its floor, a plurality of recesses in the upper side of such ledge, a burner-opening in the side-wall of the heating-chamber extended into each of 20 the said recesses, and a burner applied to each of said burner-openings, the gases therefrom being mixed in the said recesses and deflected upwardly by the ledge, as and for the purpose set forth.
- 25 5. A metal heating-chamber having a door-opening at one end and a rear wall at the opposite end, rails extended from the doorway through the rear wall, outlet ball-passages extended through the rear wall with the rails continued therein, and means 30 for closing the outer ends of the passages.
6. In a metal heating-furnace, the combination, with a heating-chamber having a door-opening at one end and a rear wall at the opposite end, of grooved rails extended 35 through the doorway to the rear wall, ball-passages extended through the rear wall with the rails continued therein, balls fitted to the grooved rails, and a car-body fitted to the tops of the balls to move thereon, and 40 hinged flaps closing the outer ends of the ball-passages, and permitting the balls to move automatically from the same through the chamber floor to the other end of the flaming-gas-duct to introduce the flaming 45 gas thereinto, and an outlet flue extended into the ledge near such downgoing duct.
7. A metal-heating chamber having a door-opening at one end and a rear wall at the opposite end, rails extended from the 50 doorway to the rear wall, outlet ball-passages extended through the rear wall with the rails continued therein, and means for closing and opening the outer ends of the 55 passages.

In testimony whereof I have hereunto set my hand.

WALTER S. ROCKWELL.
